Patented July 8, 1913.

UNITED STATES PATENT OFFICE.

ANDREW COCHRAN, OF TRENTON, NEW JERSEY, ASSIGNOR TO COCHRAN, DRUGAN & CO., OF TRENTON, NEW JERSEY, A CORPORATION OF NEW JERSEY.

SIPHON WATER-CLOSET.

1,067,096.

Specification of Letters Patent.

Patented July 8, 1913.

Application filed April 13, 1911. Serial No. 620,937.

To all whom it may concern:

Be it known that I, ANDREW COCHRAN, a citizen of the United States, and a resident of Trenton, Mercer county, New Jersey, have invented certain Improvements in Siphon Water-Closets, of which the following is a specification.

My invention relates to water closet bowls designed to be emptied by siphonic action; and the object of my invention is to provide an improved form of flushing discharge or outlet for water at the rear wall of the bowl, designed more particularly for use with what are known as reverse trap closets; that is to say, those having the trap and siphon discharge at the rear instead of the front of the bowl. It is well known that such closets require more water or greater force to effect flushing of the same, for the reason that the discharge of the flushing water to the bowl cannot be directed to the ascending leg of the siphon passage, but must take a rearward movement around the web forming the rear wall of the bowl and the top wall of the ascending leg of the siphon and normally dipping into the water in the bowl to form the desired seal. Difficulty therefore has been experienced in the use of closets of this type when attempting to flush them with water from a low-down tank; it being substantially impossible to get a satisfactory flush under this slight head of water.

In my Patent No. 934,422, I have described a construction of bowl in which the water discharge thereto is divided, substantially half of the flushing water passing to the rim which is provided with outlets entirely around the same, while the balance passes to a discharge outlet opening into the bowl at the rear of the same; the port of such outlet opening substantially flush with the surface of the bowl and directing to the bowl a large volume of water concentrated at one point and assisting materially in effecting the primary discharge of a portion of the contents of the bowl sufficient to effect the desired choke or fill of the descending leg of the siphon, cutting off the air whereby a vacuum is produced and siphonic action induced. In the patented structure the siphon passages are at the front of the bowl. I have discovered that such arrangement of discharge may be employed with highly advantageous and sat-

isfactory results in a reverse trap closet, and that by concentrating a large proportion of the main supply for passage through an outlet at the rear of the bowl, it will produce a forceful discharge of the contents of the bowl and quickly fill the discharge leg of the siphon, inducing siphonic action rapidly, and very materially improving the operation of said reverse trap closets.

The principal object of my invention is to produce a strong stream of water for the initial flow or discharge through the down leg of the siphon where, meeting obstructions, it will film across said passage and insure the desired siphonic action.

A further feature of my invention is the enlarged chamber at the upper part of the ascending and descending legs of the siphon; the bowl having bulging projections forming enlarged internal spaces which are partly divided by a median rib, while a further feature of my invention is the placing of the discharge outlet from the descending leg of the siphon in such position as to permit of a closer "roughing in" when the closet is set up for use.

My invention may be embodied in various types of reverse trap closets, and in the accompanying drawings I have shown several forms embodying my invention, in which:

Figure 1, is one construction of siphon closet bowl in which my invention may be embodied; Fig. 2, is a sectional plan view on the line *a—a*, Fig. 1; Fig. 3, is a sectional view on the line *b—b*, Fig. 1, and Fig. 4, is a sectional view of the same character as Fig. 1, showing a modified arrangement embodying my invention.

In flushing closets of this type, I have discovered that efficiency in action is materially enhanced by the delivery to the bowl of the flushing water under considerable head or force; that is to say, the reverse passage in the bowl requiring as it does the change in the movement of the water toward the rear instead of toward the front, tends to cause the bowl to fill up without causing a sufficiently heavy flow over the weir or dam between the ascending and descending legs of the siphon passage as to insure proper filling of the discharge leg with sufficient water to produce a partial vacuum and induce siphonic action. By dividing the flow in

the manner in which I have done, however, and providing for the discharge of a considerable volume of water directly at the rear of the bowl, I am able to carry over 5 very quickly the desired amount of water to induce siphonic action.

1 represents the bowl; 2 the flushing rim; 3 the ascending leg of the siphon passage; 4 the descending leg; 5 the weir between 10 the passages, and 6 the outlet from the descending leg. It will be noted in all instances that said outlet is smaller in area than the lower portion of the descending leg, and such condition produces a choking 15 action which facilitates the siphonic discharge.

At the rear of the bowl, an inlet for the delivery of flushing water directly is provided, indicated at 7, and the front rear wall 20 of the bowl opposite this inlet is arranged to divide the stream so that part of the same will go to the flushing rim 2, while the balance will enter the passage 8 opening into the bowl through the rear wall of the same 25 with its outlet flush with the surface of such wall. By this means I am able to concentrate considerable force through this discharge passage which will have the effect of raising the contents of the bowl into the 30 ascending leg of the siphon quickly and with sufficient force to provide the desired choke at the discharge outlet to insure siphonic action.

The descending leg of the siphon passage 35 has a series of zones or spaces between the weir 5 and the discharge outlet 6 which will be more fully described hereinafter. The width of the ascending leg in one plane, for instance the plane of the section shown in 40 Fig. 1, is approximately three inches, while in the plane substantially at right angles to this, the width is approximately five inches, and this width continues to the junction with the descending leg so that an enlarged chamber 45 9 is presented at the top of said descending leg. This chamber is provided with a pair of enlargements 10 formed in the rear wall of the bowl, with a depressed central portion 11; the inner surface of said enlargements being continuations of the curved wall 50 at the top of the chamber leading from the upper wall of the ascending leg of the siphon.

Within the descending leg or passage of 55 the siphon a zig-zag channel is provided. To this end the rear wall of the structure is provided with a ledge or shelf 12 substantially opposite a bend 13 in the bore of said descending leg, and from said shelf the 60 passage, with paralleling walls 14 and 15, descends at a slight angle pointed rearwardly to a bottom shelf 16 in said descending leg, which shelf is disposed rearwardly of the discharge outlet 6, while the forward 65 wall of the said outlet is in line with a

curved wall 17 of said channel or passage extending to and joining the diagonally disposed wall 15 at the point 18. It will be seen, therefore, that the initial flow of water over the weir 5 will strike the shelf 12 and 70 falling on the same will be deflected across the bore of the passage of said descending leg, cutting off the air, producing a partial vacuum and inducing siphonic action. The presence of the enlarged space at the top of 75 the ascending leg gives space for a large volume of air, and consequently when the discharge from the bowl nears its end, the force of the flow will slow down, breaking the siphon and insuring sufficient water 80 within the bowl as an after fill to make the desired seal, the height of which is governed by the weir 5.

In Fig. 4, I have shown a modified construction of the descending leg of the siphon 85 in which I form an enlarged chamber in the lower part of the same from which the discharge outlet leads. The wall opposite the ledge or shelf 12^a is curved as indicated at 20 and a projection 21 is provided substantially midway between the weir 5 and the bottom wall of the descending leg of the siphon which has a bottom shelf 16^a to the rear of said discharge outlet. Toward the front of said discharge outlet, the wall is 90 curved as indicated at 22, while the rear wall of said descending leg below the ledge or shelf 12^a is also curved as indicated at 23. The water in flowing over the weir 95 strikes the shelf or ledge 12^a and is deflected 100 to the curved wall 20 where, striking the projection 21, it will be shot in the reverse direction and strike the bottom shelf 16^a. In this zig-zag course air will be cut off, creating a partial vacuum and inducing the 105 desired siphonic action.

It will be observed upon reference to Figs. 1 and 4 of the drawings that I provide a construction of bowl in which the discharge outlet 6 is disposed well toward the rear of 110 the bowl, so that closets made in accordance with my invention permit of closer "roughing in" when set up for use; the structure shown in Fig. 4, roughing in a little closer than that shown in Fig. 1.

I claim:

1. A water closet bowl having a siphon conduit comprising intake and discharge legs, the upper part of the discharge leg being enlarged to provide a chamber for the presence of air and having a central projecting portion for dividing the stream, said discharge leg being contracted below the chamber at a point substantially opposite the meeting point of the divided body of 120 water.

2. A water closet bowl having a siphon conduit comprising intake and discharge legs, the upper portion of the discharge leg being enlarged to provide a chamber for the 130

presence of air and having a central projecting portion for dividing the stream, said discharge leg also having a flat shelf just below the dam at the top of the intake leg 5 and receiving the impact of the water discharged therefrom.

In testimony whereof, I have signed my

name to this specification in the presence of two subscribing witnesses.

ANDREW COCHRAN.
